UNITED STATES PATENT OFFICE.

WILLIAM B. ATKINSON, OF BOWLING GREEN, KENTUCKY; BOWLING GREEN TRUST COMPANY, EXECUTOR OF SAID WILLIAM B. ATKINSON, DECEASED, ASSIGNOR TO A. G. SCHWAB & SONS, OF CINCINNATI, OHIO, A PARTNERSHIP COMPOSED OF JULIAN G. SCHWAB, LOUIS LANGE, AND HERBERT C. SCHWAB.

CLOCK ATTACHMENT.

Application filed November 10, 1923. Serial No. 672,958.

This invention relates generally to the art of horology and is particularly directed to mechanism, attachable to an ordinary clock, for increasing the winding interval thereof.

5 The invention is particularly applicable to cheap commercial clocks in which one of the main objections is the necessity for frequent winding. The invention herein provides for increased winding interval by furnishing a larger stronger spring, mounted independently of the clock, and having dimensions larger than the ordinary clock spring, and thus, while the size and propelling strength of the spring is materially increased, the number of turns required to 10 fully wind the larger spring will be substantially the same as that of a smaller spring.

An object of the invention is, therefore, to 20 provide means attachable to a clock, and to the winding and propelling shaft thereof, whereby a clock having a short winding period can be conveniently and quickly converted into one having a longer winding period, with only a slight modification of the 25 clock mechanism. For example, a standard commercial eight day clock can be converted into a 96 or 100 day clock. Thus, the frequency of clock winding periods can be decreased without materially changing the 30 clock mechanism, and a clock of short winding period can be converted at small expense into one of longer winding period.

Another object is to provide a device as a 35 separately mounted attachment for a clock, which includes in addition to a propelling mechanism providing a long winding interval, a calendar attached to and operable by said propelling mechanism and including co-operative dials automatically operable for indicating months and days of the month, in substantial synchronism with the clock to which the device is attached.

Another object is to provide propelling or 40 transmission means for a clock as an attachment independently mounted, and having a powerful spring comprising substantially the standard numbers of whirls or coils, said spring being transmittingly connected to the power, winding shaft, or arbor of the clock 45 in such manner that the proper amount of power is applied to the shaft for propulsion

thereof while the time of winding interval of the spring is increased.

Another object is to provide a clock wind-up signal and signal operating device automatically operable by the expanding clock spring as the same approaches fully unwound position. The signal is adapted to call attention to the owner or attendant that 55 the clock should be rewound.

Another object of the invention is to provide transmission means between a separately mounted spring actuated motor, and a clock mechanism, for changing power ratios 60 between the motor and clock mechanism.

The use of springs, in which expansion and contraction takes place in a plane at right angles to the axis of the winding shaft requires that the number of coils or whirls 65 be such as to approximately procure uniform propelling force throughout the period of unwinding or expansion of the spring. Various devices have been employed particularly for obtaining uniformity in the propelling force of the spring during the first 70 part of the unwinding propulsion movement. It has been found that a spring having a certain number of coils is best suited for approximately accomplishing this purpose 75 and, therefore, the number of coils used has been more or less standardized, and for this reason a spring having the number of coils consistent with the requirement for such uniformity of propelling force is now generally 80 used. Because of the desirability of using a spring having a standard number of coils to obtain the greatest possible uniformity of 85 propelling force and to make the device chronologically valuable, it has ordinarily 90 been the practice to decrease the interval between winding periods in lieu of increasing the number of coils, with the result that the winding operation must be more frequently 95 performed. This is particularly the case in cheap commercial spring propelled clocks, the main objection being the necessity for frequent winding. This difficulty has been 100 herein overcome by providing a larger spring of standard proportions, than could be used on a clock of a given size, and mounting the spring outside of the clock.

Other objects and certain advantages will be disclosed in the description of the draw-

ings forming a part of this specification in which drawings:

Figure 1 is a face view of a clock having my improved mechanism connected therewith.

Figure 2 is a vertical section on the line 2—2 of Figure 1.

Figure 3 is a detail section on line 3—3 of Figure 1, illustrating a portion of the calendar dial actuating mechanism.

Figure 4 is a fragmentary view illustrating mounting of the propelling spring.

The numeral 1 designates the casing of an ordinary commercial clock to which the invention in this instance, is shown applied, although the invention may be applied to other kinds of clocks wherein it is desired to decrease the winding period. A standard clock mechanism is generally indicated at 2 and comprises the usual winding and propelling shaft 3 having the usual pawl-and-ratchet connection 4 with a main drive gear 5. The escapement mechanism of the clock has not herein been shown, but the pendulum connected therewith is shown at 6. It is believed unnecessary herein to illustrate the escapement mechanism inasmuch as its operation is well known in the art.

In connecting my device the main or propelling spring of the commercial or other clock is removed and a driven member, in this instance in the form of a sprocket 7, is pinned as at 8 to the shaft. Mounted below the clock mechanism, within and to the casing 1, preferably at the back thereof, is a stub shaft 10, integral with a plate 11 which is attached by screws to the casing as a base. Rotatable upon the shaft 10 is a sprocket wheel 12 as a driving member preferably relatively of greater diameter than the wheel 7, and the two wheels are transmittingly connected by the chain 13, as transmission means connecting driving and driven members. Attached at one end as at 14 to the hub 15 of the gear 12 is a coil spring 20, adapted during winding and unwinding, for contraction and expansion in a plane at a right angle to its axis and to the shaft 10, the form and action of this spring being well known. The outer end of the spring is secured to a pin 21. By engaging a key with the outer squared end of the shaft 3, the spring or spring actuated motor may be wound in the usual manner. The spring 20 has substantially a standard number of coils or that number consistent with the requirement for uniformity in propelling force of the spring, from wound to unwound condition, so that the spring has dimensions larger than the ordinary clock spring but possesses greater power.

The attachment, including the separately mounted propelling means, also provides a calendar and operating mechanism therefor, adapted to indicate the days of the month

and the months of the year, and consisting of a day dial 30 mounted rotatably upon the outer end of the shaft 10 between opposingly related resilient friction members respectively 31, 32, the member 31 being non-rotatably and removably locked upon the shaft 10, as at 33, and the member 32 being rotatably attached on the outer counter-turned portion thereof. The dial member 30 has peripheral teeth 35 which function substantially as ratchet teeth. The dial 30 also has an outstanding pin 36 upon its front face adapted to engage notches or ratchet teeth 37 of a calendar month dial 38 removably mounted by its stub shaft 39, upon a pedestal 40 or bracket 40 attached to the back of the clock casing. The dial 38 is yieldably frictionally held against rotation by spring members 42 frictionally engaged against a circular flange 43 on the shaft 39.

The gear of the driving member has on its outer face a series of pins 44 the distance between the pins corresponding to that traveled by each pin in twenty-four hours, so that at the end of that interval a pin will engage and operate a feed mechanism hereinafter described, to rotate the dial 30 a distance equal to that between the numerals thereon, indicative of days of the month to successively bring numerals of a larger denomination beneath a stationary pointer 45 held at the outer end of the shaft 10 by a screw 46. For every complete revolution of the day dial, 30, the month dial 38 is turned by the pin 36 which engages one of the peripheral teeth of the dial and revolves the same to bring the succeeding month indication beneath the pointer. The pin 36, however, may be dispensed with and the month dial set by hand.

The device or mechanism operable by the pins 44 upon the gear 12, for rotating the calendar dial 30 is constructed and operated in the following manner:

A lever 50 is pivoted as at 51 to a bracket 52 attached to the clock casing 1, and the lever has extensions 53 and 54 engageable with the bracket for limiting oscillating movement of the lever in both directions, but particularly in its lower position. At the outer end of the lever 50 is pivoted as at 55 a finger 56 having a shoulder 57 engageable with the lever 50 for limiting downward movement of the finger. In its lowermost position shown in Figure 1, the finger 56 is disposed for engaging a tooth of the dial 30 as the finger is moved in an upward direction. Pivoted as at 60 to the lever 50 is a lever having two arms relatively right angularly related, one arm 61 forming a finger engageable by successive pins 44, and the other arm being weighted as at 62 and adapted to lie against a stop pin 63 carried by the lever. The movement of the weighted lever is thus limited in one direc-

- tion to permit a pin 44 to engage the same to raise the lever 50 and finger 56 for rotating the disk or dial 30. Thus, when the gear 12 rotates in clockwise direction, the pins 44 will successively engage the arm 61, raise the lever 50 and finger 56 and rotate the dial 30 a distance equal to that between the day indicating numerals adjacent its periphery.
- 10 A device is also provided as a signal or indicator to the owner or attendant that the clock needs winding, this device being operated by the coil spring 20 as it unwinds. When the spring is entirely unwound a wind-up signal is exposed at a point outside of the clock casing. The structure of this device is as follows:
- 20 A lever formed of any suitable material, such as wire, is pivoted at 71 to the clock casing, adjacent the spring 20, the said lever having arms 72, 73. The arm 72 has at its upper end a sheet metal tag 74 as signal member having printed thereon in this instance the words "wind-up". A slot 75 is also provided in the side of the casing through which the wind-up tag is adapted to pass for exposure of the printed words in full view at the outside of the casing. The arm 73 has a weight 76 thereon which is adapted to counterbalance the lever and bring and hold the lever and signal member within the casing after the clock has been wound. The weight 76 is juxtaposed in reference to the spring coils in such manner that when the clock has nearly run down one of the coils or whorls will engage the weight, force the same outwardly to the position shown in dot and dash lines in Figure 1, thereby disposing the signal member outside of the casing. A suitable stop clip 78 having outstanding projections 77 is attached to the casing, and the arm 72 alternately engages the projections 78 to limit movement of the lever in both directions.
- 30 It will thus be seen that when the spring has almost reached its fully expanded position its outermost coil will have engaged the weight 75, and moved the wind-up sign into full view outside of the clock casing.
- 40 When the clock is rewound the weight of the gravity actuated lever will be thrown in an opposite direction to bring the signal member within the clock casing as shown in Figure 1, in full lines.
- 50 The usual door 1^a is provided for the clock cabinet or casing, said casing acting as a base for the mounting of the clock and motor therefor, as well as the calendar device and "wind-up" signalling device.
- 60 The device for decreasing the interval between the winding periods is simple and inexpensive and may be attached to any clock in a manner similar to that illustrated herein. I do not limit myself to its particular application to commercial clocks but con-

template the use of the invention upon any clock wherein it is desired to use a spring of greater size than can be applied directly to the clock.

Having described my invention, what I claim is:

1. A propelling and calendar attachment for a clock including a spring actuated motor having a driving wheel, said wheel having spaced pins thereon, a shaft in the clock movement for propelling the same, means transmittingly connecting said wheel and shaft, a peripheral toothed calendar dial rotatably mounted adjacent said wheel, and dial advancing means intermediate said wheel and dial adapted to be engaged by successive pins, and engageable with successive teeth of said dial, whereby said dial is moved in synchronism with said clock movement.

2. In combination a propelling and calendar attachment for a clock, an independently mounted spring actuated clock propelling motor having a driving sprocket, said sprocket having spaced pins thereon, a shaft in the clock movement for propelling the same, means transmittingly connecting said sprocket and shaft, a peripheral toothed calendar dial rotatably mounted adjacent said wheel, and dial advancing means intermediate said sprocket and dial adapted to be engaged by successive pins, and engageable with successive teeth of said dial, whereby said clock is propelled and said dial is moved in synchronism with said clock.

3. A propelling and calendar attachment for a clock including a spring actuated motor having a driving sprocket, said sprocket having spaced pins thereon, a shaft in the clock movement for propelling the same, means transmittingly connecting said sprocket and shaft, a peripherally toothed calendar dial rotatably mounted adjacent said sprocket, a lever pivoted adjacent said sprocket and dial, a finger pivoted at one end of said lever, said finger having a shoulder engageable with said lever for limiting the movement of the finger in one direction to dispose the same for engagement with successive teeth of said dial so said lever is oscillated and a projection pivoted to said lever having limited movement in one direction, said projection engageable by successive pins of said sprocket to periodically raise said lever and engage said finger with said dial, whereby said dial is moved in synchronism with said clock.

4. A propelling and calendar actuating attachment for a clock including a separately mounted spring actuated motor having a driving sprocket, said sprocket having spaced pins thereon, a shaft in the clock movement for propelling the same, means transmittingly connecting said sprocket and shaft, a peripherally toothed calendar dial rotatably mounted adjacent said sprocket,

- said dial having characters thereon in spaced relation, a lever pivoted adjacent said sprocket and dial, a finger pivoted to said lever for engagement with the teeth of said dial, said finger having a stop shoulder engageable with said lever for limiting the movement of the finger in one direction, and a projection pivoted to said lever having limited movement in one direction, said projection engageable by successive pins of said sprocket to periodically raise said lever and engage said finger with said dial, whereby said dial is moved in synchronism with said clock.
- 15 5. A combination propelling and calendar attachment for a clock, including a shaft in the clock movement for propelling the same, but without the usual main spring, a

spring actuated motor having a driving member, said member having spaced pins 20 thereon, means transmittably connecting said driving member and propelling shaft of said clock, a peripherally toothed calendar dial rotatably mounted adjacent said rotated element, a lever pivoted adjacent said element 25 and dial, said lever having a finger adapted to engage successive teeth of said dial, and a projection upon said lever engageable successively by said pins for actuating said finger for periodical engagement with and 30 rotation of said dial in synchronism with said clock.

In witness whereof, I hereunto subscribe my name.

WILLIAM B. ATKINSON.
